(57) **CLAIM**

The ornamental design for a motion assisting device, as shown and described.

DESCRIPTION

FIG. 1 is a front view of a motion assisting device showing our new design;

FIG. 2 is a rear view thereof;

FIG. 3 is a top view thereof;

FIG. 4 is a bottom view thereof;

FIG. 5 is a right view thereof, the left view thereof being a mirror image of the right view; FIG. 6 is another front view thereof showing a use state; and,

FIG. 7 is another rear view thereof showing a use state. The broken lines shown in FIGS. 6 and 7 depicting a wearer represents environmental subject matter that forms no part of the claimed design. The remaining broken lines shown in the figures depict portions of the motion assisting device that form no part of the claimed design.

1 Claim, 7 Drawing Sheets
